Fig. 8.

UNITED STATES PATENT OFFICE.

PETER SARTORY, OF BAYSWATER, LONDON, ENGLAND.

STEAMING TUBE.

Original application filed August 4, 1924, Serial No. 730,122. Divided and this application filed December 24, 1924. Serial No. 757,935.

To all whom it may concern:

Be it known that I, PETER SARTORY, a subject of the King of Great Britain and Ireland, residing at Bayswater, London, England, have invented certain new and useful Improvements in Steaming Tubes, of which the following is a specification.

This invention relates to steaming tubes for use in steaming a tress of hair coiled upon a curler in waving and curling operations.

The main object of the invention is to provide a suitable construction of closure at the "tip" end, which can be easily passed over the end of the steaming tube with one hand while the other is holding the curler with the tube thereover, and by a simple turn engage and hold the curler so as to make a steam tight closure at the root end.

A further object is to construct a steaming tube adapted for safe and easy self application and manipulation by persons desiring to curl and wave their own growing hair.

In the accompanying drawings is illustrated a preferred construction according to the invention.

Fig. 1 is a side view partly in section illustrating a curler and an exothermic heater used in a steaming tube according to the invention.

Fig. 2 is an end view of a split sleeve for positioning the heater in the tube.

Figs. 3, 4 and 5 are respectively external side and opposite end views of a convenient steaming tube adapted for use in combination with a chemical heating pad for self use in curling and waving hair, while

Figs. 6 and 7 are respectively longitudinal and transverse cross sectional views illustrating the application thereof in combination with a chemical heating pad or jacket.

Fig. 8 is a detail view further illustrating the adjustable cap of the steaming tube shown at Figs. 3 and 6.

Fig. 9 is a plan view illustrating the construction of a closure for the steaming tube.

Referring to the drawings:

The tress of hair 1 is coiled on the mandrel 2 of a tubular curler which includes a rod 2^b passing through the mandrel carrying at one end a closure for the root end 4 of the steaming tube 5; and near the other end a

nut member 2^c, as clearly shown in Fig. 6. Rotation of the nut member 2^c causes relative movement between the mandrel 2 and the rod 2^b, thus bringing the root end closure on such rod against the boss or cross piece 2X (Fig. 9) on the root end of the mandrel 2, and so firmly clamping the ligament end of a hair tress 1 between the boss or cross piece 2X on the mandrel and the root end closure on the rod. In the construction shown the closure includes a rigid plate 3^a sandwiched between rubber washers 3 and 3^b all being pierced by the rod 2^b the end of which is returned through the closure, as shown in Fig. 9, to position the closure on the rod. This curler construction and closure is not claimed herein as novel per se, and is not herein further described, the construction and operation being set out in my U. S. Patent No. 1,524,721. The root end 4 has a seating washer 4^a with which the closure cooperates to form a steam tight closure, the curler being disposed as an axial member for the tube 5. The seating washer is pierced by two guide pins 4^b (see Fig. 1, 3 and 4) which guide the root end closure to the seating washer 4^a. The tip end 6 of the tube is open, but in use is closed by a removable and adjustable cap 7.

The tip end of the curler rod 2^b extends beyond the tip end 6 of the tube, and is provided with a shoulder 2^a, and the cap 7 is centrally perforated, as indicated at 7^a, to allow the cap to be passed over the shoulder to engage the tip end of the steaming tube.

Externally on the tube at the tip end is provided a lug 8 (in the construction shown, a tube, for the purpose hereafter explained), and the cap 7 has a flange 9 which is helically slotted, as indicated at 10, and the flange is of such length and the lug 8 so disposed that the latter engages in the slot when the cap is located on the tube.

On the cap is fixed by one end a spring detent 11 constructed to constrict the opening 7^a; the detent is flexible enough to let the cap be passed over the shoulder 2^a, but immediately afterwards engages behind it, so that the curler is automatically secured in the tube; the final sealing of the closure at the root end is then easily obtained by rotating the cap as if to remove it from the tube whereon the slot bearing on the lug 8

causes the cap to be forced axially of the tube with the curler by reason of the catch engaging the shoulder, thereby forcing the closure on the seating 4^a steam tight at the 5 root end of the steaming tube.

In the construction shown the detent straddles the aperture and is provided on the free end with a lip 12, which facilitates the release of the curler from the tube 5.

10 To release the tube the detent is lifted by the tip after the cap has been reversely rotated whereon it clears the shoulder, and the cap can then be passed over the shoulder, the steaming tube being afterwards drawn 15 off the curler.

It will be observed that the engagement and release of the curler is a very simple act, easily accomplished by persons attending to their own toilet.

20 In order to support the tube during self application and manipulation, a ring 13 is provided on the top of the tube 5, as shown, and a handle 14 is employed which has a hook 15 (Fig. 4) constructed to engage and 25 support the ring, the handle being of such length as to be held comfortably while steaming is going on. A grip for the handle is conveniently obtained by looping the handle, as shown at 16.

30 The steaming tube illustrated is shown associated with an autogenous heater which does not form part of the present invention. The heater is supported on a perforated heat-conducting tube 17 loosely disposed 35 over the tress, and the heater comprises a layer of a chemical substance 18 which will react exothermically with a liquid reagent, preferably the substance is calcium oxide and the reagent water, and an outer layer 40 of fibrous material 19, which is such as to act as a distributor of the reagent to the chemical layer.

The chemical layer is enclosed in an envelope 20 of porous material, preferably 45 divided by stitching into three pockets, as indicated in Fig. 7, to limit movement of the chemical substance 18, and the fibrous material maintained in position by binders 21.

50 The reagent—water—is distributed to the fibrous layer by a pipe 22 disposed lengthwise of the steaming tube on the inside thereof, and is perforated; the tube terminating in the tubular lug before referred to. Water can be introduced at 8, and passing out of the tube soaks and saturates the fibrous layer 19, which then acts as a distributor to the chemical layer.

55 For still further convenience the tubular lug 8 which is the water inlet, may be provided with an india rubber bulb 23 and tube 24 for forcing water into the steaming tube 5.

60 Where it is only required to treat the root end of a tress, a short heater can be

used in conjunction with a split sleeve 25, as shown in Figs. 1 and 2, the sleeve having lugs 26 which bear against the end of the pad, and also being split to pass along the pipe 22.

I claim:—

1. In combination, a steaming tube, a closure for the root end of the tube, an axial member connected to said closure and extending through said tube beyond the tip end thereof, a shoulder on the axial member at the tip end thereof, a lug on said tube at the tip end, a cap for the tip end, a helically slotted flange to said cap extending beyond the lug, the cap having a central aperture to pass over said axial member, a spring detent fixed on said cap for constricting the central aperture behind said shoulder, so that on rotation of the cap on the steaming tube, the cap bearing on the lug is forced axially of the tube by reason of the detent engaging the shoulder of the axial member to force the closure of the axial member steam tight against the root end of the steaming tube. 80

2. In combination a steaming tube, a closure for the root end of the tube, an axial member connected to said closure and extending through said tube beyond the tip end thereof, a shoulder on the axial member at the tip end thereof, a lug on said tube at the tip end, a cap for the tip end, a helically slotted flange to said cap extending beyond the lug, the cap having a central aperture to pass over said axial member, a spring detent disposed diametrically on said cap straddling said aperture and fixed to said cap by one end, a lip on the other end of said detent, the detent normally engaging under said shoulder of the axial member but adapted to release the latter from said cap when lifted by said lip from the cap, the arrangement of the cap and lug being such that on rotation of the cap on the steaming tube the cap bearing on the lug is forced axially of the tube by reason of the detent engaging the shoulder of the axial member to force the closure of the axial member steam tight against the root end of the steaming tube. 100

3. A steaming tube comprising a tubular body portion, having at the root end a seating for a closure, a lug near the tip end and a cap for the tip end, said cap having a central aperture for receiving the end of a curler, a helically slotted flange extending beyond the said lug and a spring detent fixed to the cap and constructed to constrict the aperture in the cap, for the purpose set forth. 110

4. A steaming tube comprising a tubular body portion having at the root end a seating for a closure, a tubular lug near the tip end, a perforated pipe connected to said tubular lug and disposed lengthwise inside

the steaming tube, and a cap for the tip end, said cap having a central aperture for receiving the end of a curler, a helically slotted flange extending beyond the said lug 5 and a spring detent fixed to the cap and constructed to constrict the aperture in the cap, for the purpose set forth.

5. A steaming tube comprising a tubular body portion having at the root end a seating for a closure, a tubular lug near the tip end, a perforated pipe connected to said tubular lug and disposed lengthwise inside the steaming tube, a cap for the tip end, said cap having a central aperture for receiving the end of a curler and including a helically slotted flange extending beyond the said lug, a spring detent disposed diametrically on said cap straddling said aperture and fixed to said cap by one end, and a 10 lip on the other end of said detent, the detent being constructed to constrict the aperture in the cap, for the purpose set forth.

6. In combination, a steaming tube, a 25 closure for the root end of the tube, an axial member connected to said closure and extending through said tube beyond the tip end thereof, a shoulder on the axial member at the tip end thereof a tubular lug on 30 said tube at the tip end, a perforated pipe connected to said tubular lug and disposed lengthwise inside the steaming tube, a cap for the tip end, a helically slotted flange

to said cap extending beyond the tubular lug, the cap having a central aperture to 25 pass over said axial member, a spring detent disposed diametrically on said cap straddling said aperture and fixed to said cap by one end, a lip on the other end of said detent, the detent normally engaging under 30 said shoulder of the axial member but adapted to release the latter from said cap when lifted by said lip from the cap, the arrangement of the cap and lug being 35 such that on rotation of the cap on the steaming tube, the cap bearing on the lug is forced axially of the tube by reason of the detent engaging the shoulder of the axial member to force the closure of the axial member steam tight against the root 40 end of the steaming tube.

7. A steaming tube comprising a tubular body portion, having at the root end a seating for a closure, a lug near the tip end and a cap for the tip end, said cap having a 55 central aperture for receiving the end of a curler, a helically slotted flange extending beyond the said lug and a spring detent fixed to the cap and constructed to 60 constrict the aperture in the cap, a ring on said steaming tube and a handle member including a hook for detachably engaging the ring and a grip formed by looping the member upon it, as set forth.

In testimony whereof I affix my signature.
PETER SARTORY.
